COUPLING DEVICE OF VACUUM CLEANERS

Klara Content, Voorburg, Netherlands, assignor
to Thabur, Industrieel en Technische Handel-
maatschappij N. V., The Hague, Netherlands

Application June 22, 1939, Serial No. 280,497
In the Netherlands June 17, 1938

3 Claims. (Cl. 285—177)

This invention relates to coupling devices for connecting a vacuum cleaner tube or another detachable part to a vacuum cleaner casing. More particularly the invention is concerned with a bayonet coupling of the kind in which the coupling parts fixed to the vacuum cleaner casing is provided with one or more inwardly projecting guide members, whilst the other part of the coupling is connected to the vacuum cleaner tube and consists of a revolvable cylindrical ring which is provided with tangential helicoidal surfaces at the outside, which surfaces are adapted to cooperate with the guide members of the fixed coupling parts.

One of the objects of my invention is to devise a new and improved coupling device of this kind, which is efficient in construction, simple in manufacture and easy in handling. Another object of my invention is to provide a coupling device which is particularly suitable for use in vacuum cleaners.

Another object of my invention is to devise a coupling device in which the detachable coupling part has no projecting parts, which on a vacuum cleaner tube can catch in carpets and furniture e. g. during putting away of the vacuum cleaner and can cause other damages.

Another object of my invention is to provide a coupling device which cannot be turned through so that the coupling does not bite.

A still further object of my invention is to provide a coupling device in which the locking cams are well protected and enable at the same time a good guiding and rigid fixation of the detachable coupling part in such a manner that the coupling cannot get loose prematurely.

Another object of my invention is to provide a coupling device which can be made very durable and enables at the same time a very efficient tightening.

Another object of my invention is to provide a coupling device, having no loose or detachable parts at the detachable coupling part.

In contrast to the known constructions of the kind referred to according to the invention the bayonet coupling comprises a coupling part fixed to the vacuum cleaner casing and consisting of a stepwise widening annular member of which the widened part of the opening of the member is adapted to receive the revolvable part of the detachable coupling part and is provided between the bottom and the free edge with a number of inwardly projecting cams or other guiding members, whilst the other coupling part consists of a mainly cylindrical ring which is revolvably con-

nected to the end of the vacuum cleaner tube and provided with tangential helicoidal surfaces at the outside being adapted to cooperate with the said fixed cams or guide members of the fixed coupling part, the helicoidal surfaces of the revolvable ring being carried out as grooves hollowed out in the material of the ring, running substantially in the circumferential direction thereof, and each corresponding with longitudinal grooves opening to the free end edge of the revolvable ring.

In this connection it is observed that the provision of a single groove in the detachable coupling part, in such a manner that this groove is adapted to cooperate with a projection at the inside of the fixed coupling part is known in itself. In the known construction referred to the coupling, however, is not a bayonet coupling, but a friction coupling in which the coupling parts are clamped together in the coupling position by means of conical friction-surfaces. Furthermore, the grooved coupling part is rigidly connected to the vacuum cleaner tube so that the coupling can easily get loose in spite of the bayonet safety-locking.

The recesses of the detachable coupling part forming the helicoidal surfaces according to the invention have preferably a depth which is about equal or smaller than the half thickness on that place of the material of the ring forming this coupling part. In this manner the coupling part connected to the vacuum cleaner tube becomes considerably stronger, whilst on the other hand this construction enables a very efficient tightening between the two cooperating coupling parts. This tightening occurs preferably by providing the fixed coupling part in the bottom wall with a tightening ring which, in the coupling position of the two coupling parts, covers the joint between the bent out revolvable edge of the vacuum cleaner tube and the part of the detachable coupling part surrounding this edge of the tube. In this manner dust is prevented from getting between the two coupling parts.

The invention will now be described with reference to the accompanying drawing, in which a preferred embodiment of the invention is shown. In the drawing:

Fig. 1 shows a longitudinal section of a coupling device according to the invention,

Fig. 2 a front view on a somewhat reduced scale of the coupling part connected to the vacuum cleaner tube,

Fig. 3 shows a side view of this coupling part on a reduced scale and

Fig. 4 shows a front view on a somewhat reduced scale of the coupling part fixed to the vacuum cleaner casing.

Referring to the drawing 1 indicates a flexible vacuum cleaner tube which is provided at the end with a rigid, e. g. metal, sleeve 2 which is revolvably connected to the coupling part 3 fixed to the vacuum cleaner tube. The revolvable connection is obtained in this case in that the sleeve 2 runs through the coupling part 3 and this latter is provided internally with an annular narrowing 4 on both sides of which the sleeve is somewhat widened. Thus the sleeve can rotate freely with respect to the coupling part 3, but lies absolutely fixed in axial direction.

The coupling part fixed to the vacuum cleaner tube consists in the shown embodiment of a mainly cylindrical front part 5 with grooves 6, hollowed out in the material thereof, and having a tangential helicoidal surface 7. The grooves 6 are closed at one end and have at the end, nearest to the free edge of the front part 5, a connection with an axial or approximately axial groove 8, opening to the free end of the revolvable ring 5 (Fig. 3). The rear part 9 is provided with a milled edge 10 in order to facilitate turning the ring 5 for coupling and decoupling purposes.

The coupling part fixed to the vacuum cleaner casing consists mainly of an annular member 11, which is provided with internally projecting cams or guide members 12. In the shown embodiment three cams 12 are provided, but if desired also one or another number of cams can be used.

The cams 12 have such dimensions that they can easily be brought into the grooves 6 through the passages 8.

The tightening is obtained by means of a tightening ring 13, which is connected to an internal flange or wall 14 of this coupling part. This can e. g. take place by inserting the ring in an annular dovetailed groove of the flange. The dimensions of the cooperating coupling parts are in this connection to be chosen in such a manner that the front edge of the coupling part fixed to the vacuum cleaner tube lies in the coupling position near to the flange 14. In order to prevent eventual leakages along the sleeve 2 and the coupling part fixed to the vacuum cleaner tube, the sleeve can be bent out against the front edge of this coupling part. In this manner it can be obtained that the end edge 15 of the sleeve abuts also against the tightening ring 13.

The coupling part 11 can e. g. be connected to the vacuum cleaner casing 10 with screws 16, but also with a threaded end part 17 as shown in dotted lines in Fig. 1 or in another manner.

The invention is above described with reference to a preferred embodiment, but it will be clear that the invention is not restricted to this embodiment and that numerous changes and omissions could be made without departing from its spirit. Thus e. g. the helicoidal surfaces 7, instead of being formed by recesses in the material, can also be formed as projecting cam-surfaces, which together form a ring with recesses.

What is claimed, is:

1. A coupling device for detachably connecting a vacuum cleaner tube to a vacuum cleaner casing comprising an annular member rigidly secured to the casing and an annular member rotatably connected with the tube, the first annular member presenting an internal annular recess defined by a tubular portion coaxial with the annular members and a vertical annular flange adjacent the casing, the second annular member embodying a portion adjacent the free end of said tubular portion for effecting rotation of the member and a tubular portion extending into the recess in the first member, cam lugs projecting inwardly from said first tubular portion and angular grooves extending partially through said second tubular member from the outer wall thereof, the grooves embodying portions parallel with the axes of said members for initially receiving said lugs and circumferential portions having cam walls for receiving said lugs and effecting movement of said members toward each other upon rotation of the second member.

2. A coupling according to claim 1 together with a seal ring seated in an annular groove in said vertical flange and projecting into said recess for engagement of the free end of said second tubular portion therewith.

3. A coupling according to claim 1 wherein the rotatable connection between the second annular member and the tube comprises an elongated sleeve having a portion thereof surrounding an end of the tube and connected thereto and a portion projecting beyond the end of the tube, a circumferential recess in the projecting portion of the sleeve, and a circumferential rib on the inner wall of said second tubular portion extending into said recess.
